(57) **CLAIM**

The ornamental design for an electronic cable locking clip and connector, as shown and described.

DESCRIPTION

FIG. 1 is an upper perspective view of an electronic cable locking clip and connector showing our new design;

FIG. 2 is a lower perspective view thereof;

FIG. 3 is a top plan view thereof;

FIG. 4 is a bottom plan view thereof;

FIG. 5 is a right side elevational view thereof showing the clip in an engaged position;

FIG. 6 is a left side elevational view thereof showing the clip in an engaged position;

FIG. 7 is a rear elevational view thereof; and,

FIG. 8 is a front elevational view thereof.

The broken lines in the figures are for illustrative purposes only and form no part of the claimed design.
